UNITED STATES PATENT OFFICE.

ARCHER L. KNAPP, OF DETROIT, MICHIGAN, ASSIGNOR TO PACKARD MOTOR CAR COMPANY, OF DETROIT, MICHIGAN, A CORPORATION OF MICHIGAN.

DESIGN FOR A DOME LIGHT.

Application filed February 7, 1925. Serial No. 12,292. Term of patent 3½ years.

To all whom it may concern:

Be it known that I, ARCHER L. KNAPP, a citizen of the United States, residing at Detroit, Wayne County, State of Michigan, have invented a new, original, and ornamental Design for a Dome Light, of which the following is a specification, reference being had to the accompanying drawings, forming a part thereof.

Fig. 1 is a plan view of a dome light embodying my invention; and

Fig. 2 is an elevation of the dome light shown in Fig. 1.

I claim:

The ornamental design for a dome light, as shown.

In testimony whereof I affix my signature.

ARCHER L. KNAPP.
